[57] **CLAIM**

The ornamental design for a shipping container for jewelry items and watch bands, as shown and described.

DESCRIPTION

FIG. 1 is a perspective view of a shipping container for jewelry items and watch bands showing my new design; FIG. 2 is a perspective view of the base thereof without the cover;

FIG. 3 is a perspective view of the cover thereof without the base;

FIG. 4 is a left side elevational view of FIG. 2, the right side elevational view being a mirror image thereof;

FIG. 5 is a top plan view of FIG. 2;

FIG. 6 is a left side elevational view of FIG. 3, the right side elevational view being a mirror image thereof; and, FIG. 7 is a top plan view of FIG. 3.

The base and cover of the shipping container in FIGS. 2-7 are shown separately for clarity of illustration. The bottom surface is plane and unornamented.

FIG. 1
